IRON HOLDER

Roselle Harper, Hollywood, Calif.

Application January 3, 1955, Serial No. 33,779

Term of patent 14 years

(Cl. D49—6)

Fig. 1.

Fig. 2.

Fig. 3.

Fig. 4.

Fig. 1 is a perspective view of an iron holder embodying my new design in a position when in use on an ironing board.

Fig. 2 is a side elevational view thereof in its normal position when not in use on an ironing board.

Fig. 3 is a front elevational view; and

Fig. 4 is a rear view thereof.

I claim:

The ornamental design for an iron holder, as shown.
